UNITED STATES PATENT OFFICE

EARL E. HARRINGTON, OF BALTIMORE, MARYLAND

CATAMENIAL APPLIANCE

Application filed June 15, 1928. Serial No. 285,547.

This invention relates to a catamenial appliance and has for one of its objects to provide and improved pad-carrier and protector for devices of this character whereby the pad may be readily attached to or removed from the carrier and protector.

Other objects and advantages will appear as the invention is more fully disclosed in the following specification.

10 The invention is illustrated in the accompanying drawing, wherein,—

Fig. 1 shows the improved device attached to and suspended from a body band with a pad in place thereon, the parts being shown 15 in perspective.

Fig. 2 illustrates the pad-carrier and its attaching tabs as viewed from the under side.

Fig. 3 shows the pad-carrier, tabs, pad-clamps and pad as viewed from the upper 20 side thereof, and

Fig. 4 illustrates a cross-section through the pad-carrier as viewed on the line 4—4 of Fig. 2.

Referring to the drawing, the numeral 5 25 designates a pad-carrier and protector of a general rectangular shape and preferably formed of a sheet of thin rubber or moisture-proof material.

Near each end, but spaced from the end 30 edges 6 thereof, the pad-carrier and protector has cross-wise reinforcements 7 and 8 therein which comprise fabric strips embedded or cured in the rubber sheet.

Perforations 9 are provided in the pad- 35 carrier in spaced relation, and these perforations extend through the rubber sheet as well as through the fabric strips or reinforcements 7 and 8.

The perforations 9 are arranged in pairs 40 in that one of them passes through the pad-carrier and strip near one side of the carrier while the other passes through the pad-carrier and strip adjacent to the opposite side of the carrier.

An elastic or flexible cord 10 is fed through 45 the perforations from one side of the carrier to the opposite side thereof whereby to form two loops 11 and 12,—the loop 11 being on the under side of the carrier while the loop 50 12 is at the upper side of said carrier and is

to be utilized as a clamp as and for a purpose that will presently be more fully explained.

One loop 11 at one end of the carrier has a fabric tab 13 attached thereto while the loop 11 at the opposite end of the carrier has a 55 fabric tab 14 attached to it.

The two tabs 13 and 14 are provided for attachment to a belt structure 15, which encircles the body of the wearer but which latter forms no part of my invention.

The means employed to attach the tabs 13 and 14 to the belt structure may vary, but in the present instance, I show safety-pins 16 for this purpose.

In practice, the sanitary pad 17 of any preferred form is laid upon the upper side of the pad-carrier and protector, as shown in Figs. 1 and 3 of the drawing, and the two ends 18 of the pad are slipped beneath the loops 12. 65

When the appliance is attached to the belt-structure 15, the tabs 13 and 14 which engage the under loops 11, draw on the cords 10 and pull the loops 12 taut at the upper side of the carrier and clamp the ends 18 of the sanitary 70 pad in place against the pad-carrier and protector and hold the same from displacement.

The strain therefore on the tabs causes the clamping loops 12 to engage and hold the pad 80 while the reinforcements 7 and 8 prevent the cords from tearing the rubber of the carrier and thus maintain the upper and lower loops in the cord.

Having described my invention, I claim:— 85

1. A catamenial appliance comprising a flexible pad-carrier and protector having a looped cord passing therethrough at each end thereof, the loop of the cord extending cross-wise over the pad-supporting face of the carrier and serving to clamp the ends of a pad and means for supporting the carrier by the looped cords whereby to draw the loops in clamping engagement with the ends of the pad laid upon the carrier. 90

2. A catamenial appliance comprising a pad carrier and protector comprising a sheet of moisture-proof material having reinforcements near each end thereof with a pair of spaced perforations extending through said 100

sheet and reinforcements, a cord passing through said spaced perforations and extending crosswise over the pad-supporting surface of the carrier whereby said crosswise portion of the cord will form a clamp at one side of the carrier, and a tab attached to each cord at the opposite side of said carrier whereby when a pull on the tabs takes place on the one side of the carrier the crosswise portions of the cords will be drawn toward the opposite side of the carrier to clamp a pad thereagainst.

In testimony whereof I affix my signature.
EARL E. HARRINGTON.
